CLAIM

I claim the ornamental design for the notebook with dual notepads, as shown and described.

DESCRIPTION

FIG. 1 is a top right perspective view of the notebook with dual notepads showing my new design;

FIG. 2 is a top plan view thereof;

FIG. 3 is a bottom view thereof;

FIG. 4 is a rear view thereof;

FIG. 5 is front view thereof; and,

FIG. 6 is a side view thereof.

1 Claim, 3 Drawing Sheets
